I. D. THORNBURGH.
 APPARATUS FOR PREPARING CAN ENDS FOR THE RECEPTION OF RING LINERS.
 APPLICATION FILED MAY 17, 1916.

1,261,976.

Patented Apr. 9, 1918.

UNITED STATES PATENT OFFICE.

IVAN D. THORNBURGH, OF OAKLAND, CALIFORNIA, ASSIGNEE TO AMERICAN CAN COMPANY, OF SAN FRANCISCO, CALIFORNIA, A CORPORATION OF NEW JERSEY.

APPARATUS FOR PREPARING CAN ENDS FOR THE RECEPTION OF RING-LINERS.

1,261,976.

Specification of Letters Patent. Patented Apr. 9, 1918.

Application filed May 17, 1912. Serial No. 98,187.

To all whom it may concern:

Be it known that I, IVAN D. THORNBURGH, a citizen of the United States, residing at Oakland, in the county of Alameda and State of California, have invented certain new and useful Improvements in Apparatus for Preparing Can Ends for the Reception of Ring-Liners, of which the following is a specification.

The present invention relates to an apparatus for preparing sanitary can ends for the reception and retention of ring liners to be used as packing between the adjacent flanges of a joint or seam.

The object of the invention is to provide an apparatus for in-turning, recessing, or curling the inner bounding shoulder of a flanged can end in such manner that a portion of said shoulder will overhang a portion of the flange, and by so doing will retain a ring liner in position upon said flange. The machine is particularly adapted for use upon can ends having a straight, or non-curved flange, to provide upon such ends a means for holding or retaining an applied ring liner in position relative to said flange.

In order to comprehend the invention, reference should be had to the accompanying drawings, wherein—

Figure 1 is a front elevation of the machine.

Fig. 2 is a vertical section on the line 2—2 of Fig. 1, viewed in the direction of the arrows.

Fig. 3 is a diametrical section through a can end before being acted upon by the machine.

Fig. 4 is a sectional detail, enlarged, taken in the direction of the arrows on the line 4—4 of Fig. 1, showing a can end in its progress through the machine.

Fig. 5 is a view similar to Fig. 3 of a can end after being acted upon by the machine.

In the drawings, the reference numeral 1 designates a suitably constructed base, from which rise posts 2 carrying a journal 3 for the support, preferably in an inclined position, of a rotatable shaft 4. Said shaft 4 is rotated by means of a bevel or miter gear 5, carried upon its lower end, and meshing with a similar gear 6 upon a horizontal drive shaft 7, suitably supported by posts 8, and provided with a belt pulley 9 at its outer end. It is to be understood, however, that any suitable means may be employed for re-

tating the shaft 4, the drive mechanism and the positioning of the parts herein described and illustrated being merely a preferred form.

The shaft 4 carries on its upper end a disk 10, the peripheral edge of which is formed with an outwardly projecting guide flange 11—Fig. 4 of the drawings, having a flat face 12, and a crimping or curling flange 13, as illustrated, said curling flange being adapted to bear against the shoulder 14 of the can end 15, and to curl or dish the same, said can end being guided by the flat face 12 of the guide flange 11.

Surrounding the disk 10 and supported in the same plane as said disk by the brackets or posts 2 and 16, is a semi-circular track structure, comprising a floor plate 17 and a rim 18 having a flat-faced guide flange 19 and a curling flange 20, similar in form and function to the flanges 11 and 13 of the disk 10. The floor plate 17 is preferably cut away at the portion adjacent to the curling flange 20, as shown at 21 in Fig. 4 of the drawings, to prevent interference with the sealing flange 14' of the can end 15.

The can ends are delivered to the upper end portion 17' of the floor plate 17 by any suitable means, shown in the drawings as a belt conveyer 22, running over an end pulley 23, and driven by a sprocket 24. Sliding downward over said plate 17 by gravity, the can ends are introduced between the rotating disk 10 and the stationary rim 18, and are rolled around said track, by the rotation of said disk, and finally discharged at the point 25, Fig. 1 of the drawings.

During this passage of the can end through the machine, it is guided below by the floor plate 17 and above by the guide flanges 11 and 19, and 19, and its shoulder 14 is engaged by the curling flanges 13 and 20. The distance between said curling flanges 13 and 20 is slightly less at the discharge side of the machine than at the intake side, so that said flanges cause a gradually increasing pressure against the shoulder 14 of the can end, resulting in the crimping or dishing thereof to form a retaining groove or channel 14''. This grooving or channeling of the shoulder 14 causes the upper portion of said shoulder to overhang a portion of the sealing flange 14', and the grooving, channeling or recessing of said shoulder provides a means for retaining a ring liner in position upon said

flange when properly applied thereto in any suitable manner.

I do not wish to be construed as limiting the invention to the form and construction herein described and illustrated, inasmuch as many changes may be made therein without in any way affecting the principles of the invention. On the contrary, I wish to be understood as claiming the invention as broadly as the art will allow.

Having thus described my invention, what I claim as new and desire to protect by Letters Patent is:—

1. A machine for forming shouldered and horizontally flanged can ends prior to their reception of ring liners, for the retention of such ring liners on the exteriors of said shoulders, having in combination a rotatable member provided with a convex continuous curling flange and a contiguous overhanging flat flange, and a stationary member extending partly around said rotatable member and provided with a continuous concave curling flange opposite to the curling flange of the rotatable member and provided with a flat face arranged at a distance from the plane of the said flat flange equal to the vertical thickness of a can end, said curling flanges being intermediate the planes of said flat flange and face.

2. A machine for forming shouldered can ends for the retention of ring liners on the exteriors of said shoulders, having in combination a rotatable member provided with a convex continuous curling flange and a contiguous overhanging flat flange, and a stationary member extending partly around said rotatable member and provided with a continuous concave curling flange opposite to the curling flange of the rotatable member and provided with a flat face arranged at a distance from the plane of the said flat flange equal to the vertical thickness of a can end, said curling flanges being intermediate the planes of said flat flange and face, said members being inclined between vertical and horizontal planes.

3. A machine for forming shouldered can ends for the retention of ring liners on the exteriors of said shoulders, having in combination a rotatable member provided with a convex continuous curling flange and a contiguous overhanging flat flange, and a stationary member extending partly around

said rotatable member and provided with a continuous concave curling flange opposite to the curling flange of the rotatable member and provided with a flat face arranged at a distance from the plane of the said flat flange equal to the vertical thickness of a can end, said curling flanges being intermediate the planes of said flat flange and face, said flat face being extended to form a supporting slide for the can ends before they enter between the curling flanges.

4. A machine for forming shouldered can ends for the retention of ring liners on the exteriors of said shoulders, having in combination a rotatable member provided with a convex continuous curling flange and a contiguous overhanging flat flange, a stationary member extending partly around said rotatable member and provided with a continuous concave curling flange opposite to the curling flange of the rotatable member and provided with a flat face arranged at a distance from the plane of the said flat flange equal to the vertical thickness of a can end, said curling flanges being intermediate the planes of said flat flange and face, and a conveyer acting to deliver can ends to said flat face.

5. A machine for forming shouldered can ends for the retention of ring liners on the exteriors of said shoulders, having in combination a rotatable member provided with a convex continuous curling flange and a contiguous overhanging flat flange, and a stationary member extending partly around said rotatable member and provided with a continuous concave curling flange opposite to the curling flange of the rotatable member and provided with a flat face arranged at a distance from the plane of the said flat flange equal to the vertical thickness of a can end, said flat face being recessed opposite to the curling flange of the stationary member, said curling flanges being intermediate the planes of said flat flange and face.

In testimony whereof I have signed my name to this specification in the presence of two subscribing witnesses.

IVAN D. THORNBURGH.
